UNITED STATES PATENT OFFICE.

ROBERT L. MCINTOSH, OF CHICAGO, ILLINOIS, ASSIGNOR TO McCORD AND COMPANY, OF CHICAGO, ILLINOIS, A CORPORATION OF NEW JERSEY.

FORCE-FEED LUBRICATING SYSTEM.

1,270,182.

Specification of Letters Patent. Patented June 18, 1918.

Application filed January 2, 1913. Serial No. 739,608.

To all whom it may concern:

Be it known that I, ROBERT L. MCINTOSH, a citizen of the United States, residing at Chicago, in the county of Cook and State 5 of Illinois, have invented certain new and useful Improvements in Force-Feed Lubricating Systems; and I do hereby declare the following to be a full, clear, and exact description of the invention, such as will enable others skilled in the art to which it 10 pertains to make and use the same.

My invention has for its object to improve the construction and action of force feed lubricating systems, and is particularly directed 15 to the improvement of that type of force feed lubricating apparatus wherein the oil is delivered under pressure, and against a resisting pressure, through a so-called terminal check valve. More especially, the invention is directed to an improved 20 relative arrangement of the said terminal check valve in respect to the pump or oil forcing device of the lubricating system.

Generally stated, the invention consists of 25 the novel devices and combinations of devices hereinafter described and defined in the claim.

Terminal check valves of force feed lubricating systems are located in the delivery 30 ends of the oil delivery pipes or conduits, and their function is to retain these oil pipes full of oil, at all times and at nearly constant pressure. The terminal check valve in common use comprises a weighted check needle 35 valve which is arranged to open under a pressure which is very much less than the normal pressure which is maintained in the oil delivery pipe in the feeding action and which is also very much less than the maximum 40 pressure in the chamber which receives oil from the lubricating apparatus.

In these force feed lubricating systems, it is of the greatest importance to keep the oil delivery pipes, at all times, free from air and 45 vapor, and to keep such pipes always completely filled with a body of oil.

As a concrete illustration, the following statements may be made:

In common locomotive practice, a boiler 50 pressure of 200 pounds per square inch is maintained, and in the force feed lubricating systems usually employed, an old type of needle point gravity seated terminal check valves are employed. The steam has free

access into the valve chamber and when the 55 lubricating system is pumping against a steam pressure, the valve chamber is in communication with this pressure, and the steam pressure is exerted on the top of the weight, and on the bottom of the weight with the exception 60 of the area contact of the needle seat. The total downward pressure on the seat is equal to the weight plus the steam pressure times the top area of the weight, while the total upward pressure equals the steam pressure times the bottom area of the weight with the area of the contact of the seat 65 taken out.

When such a valve is open to the atmosphere at the outlet and the lubricator is operated, the pressure of oil in the oil pipes will be just enough to raise the needle valve. This pressure will be equivalent to the weight of the valve divided by the area of contact of the needle seat. In customary 70 practice this pressure is 25 to 60 pounds. When this valve is attached to a steam chest and the lubricator is delivering oil against the steam in the steam chest, the pressure of oil in the oil pipes will be equal to the pressure 75 of steam in the steam chest plus the ordinary pressure required to lift the valve in the first case, so that if the steam pressure in the steam chest is 200 pounds, and the resistance of the valve against the atmospheric pressure is 60 pounds, the oil pressure 80 in the pipes will be 260 pounds. If the steam pressure in the steam chest is 100 pounds, the oil pressure in the oil pipes will be 160 pounds. The oil pressure in the oil 85 pipe will always be equal to the steam pressure plus the resistance of the valve.

Assume the case of a locomotive standing still with the oil pressure in the oil pipes at 60 pounds. When the throttle is suddenly 90 opened, the steam chest pressure is increased from zero to 200 pounds, but no oil will be delivered into the steam chest until the oil pressure in the oil pipe has been built up from 60 to 260 pounds, and when the 95 throttle is shut off, oil will continue to flow out of the oil pipe until the oil pressure is reduced to, say 60 pounds, at which point the gravity valve will close and prevent further discharge.

A gravity check valve could be made 100 which would lift at 220 pounds instead of 60 pounds, and while this valve would lift

at a higher pressure than the steam pressure, say 200 pounds, the sudden opening of the throttle would add the steam pressure to the resistance offered by the check valve, 5 and no oil would be delivered into the steam until the oil pressure had reached 420 pounds. The point is that the ordinary gravity valve allows a fluctuation of pressure in the oil pipe exactly equal to the fluctuation in steam 10 pressure against which it is operating, regardless of the initial pressure which the valve by itself retains in the oil pipe.

My object was to design a valve which would maintain a nearly constant oil pipe 15 pressure regardless of the steam pressure or vacuum against which the oil was being delivered, by that means eliminating the fluctuation in oil pipe pressure due to a corresponding fluctuation in steam pressure, 20 thus insuring a constant and uninterrupted regular feed of oil to the steam chest. In other words, the oil pipe pressure would be 250 pounds regardless of whether the steam pressure was zero or 200 pounds.

25 In the above figures it is assumed that there is no loss of steam pressure between the steam chest and the inside of the ordinary gravity valve chamber. This, however, is not exactly obtained in practice, and 30 in the case of a 60 pound gravity check valve operating against 200 pounds of steam, the pressure of oil in the oil pipe would fluctuate from 235 to 250 pounds.

Many advantages are derived from my 35 improved arrangement above set forth. A constant oil pressure in the oil delivery pipe is maintained regardless of varying pressure in the steam chest, and against which steam chest pressure the lubricator pump has 40 to work. The advantage of maintaining a constant pressure in the oil pipe or conduit is that it insures a constant feed of oil into the steam chest or pressure chamber, regardless of the pressure in this chest or chamber. Stated in another way, the final desired result is obtained, to-wit, the feed of oil to the steam chests and cylinders will start when the engine starts and stop when the engine stops, so that there will be no 50 waste of oil, and there will always be a supply of oil when the engine is in action. Another advantage obtained by maintaining this constant pressure in the oil feed pipe, very much above the maximum pressure of 55 the steam chest, is that when the oil pipes are so located that they are subject to the same temperature as the boiler or engine cylinders, the oil in the conduit is at a sufficiently high pressure to more than compensate 60 for the contraction which takes place in the oil in the conduit. The volume of the oil conduit is constant and when a sufficiently greater volume of oil is forced into the conduit, the pressure in the conduit is raised to a given point. This ex-

cess amount added should be greater than the volumetric decrease which occurs when a volume of oil equal to the volume of the conduit is cooled down to atmospheric temperature from a temperature equal to that of the boiler. The pressure shown when additional oil is forced into the conduit is a direct indication of the volume of oil added. In other words, no matter what contraction of oil in the conduits due to reduced temperature, may take place, the initial pressure of the oil is sufficiently high so that it is not reduced to zero or less by this contraction of volume, and some pressure at least is retained on the oil in the conduit. 70 As long as there is any pressure of oil in the conduit, it will be impossible for any air to be drawn in. The contraction above described, due to temperature reduction, is an action which takes place when the engine is removed from service and allowed to cool off. Maintaining a high pressure in the oil conduit at all times, whether the engine is in service or out of service, prevents the drawing of any air or vapor into the 80 oil pipe or conduit, or syphoning of oil from the receiver to replace the volume reduced by contraction, such as is liable to happen under the old form of force feed lubricator, when the volume contraction in the 85 oil takes place in the said feed pipe to the extent that the volume of oil becomes less than the volume of the discharge pipe or conduit. The disadvantage of the presence of air or vapor in the oil pipe or conduit is 90 that such air or vapor must be worked out of the system before a regular delivery of oil can be maintained, the time required to rid the system of such air or vapor varying with the amount thereof. The length of time required to thus rid the system of such accumulated air or vapor may be so long that serious results may follow on account of the lack of regularity in the delivery of oil to the parts requiring lubrication. 100

Another disadvantage is that when any air is drawn into the pipes while the locomotive and the lubricating system are cold, the locomotive is again heated up, the oil in the conduits expands and the only escape for it is out the ordinary gravity check valve, provided that the heat is sufficient to increase the volume of oil enough to raise its pressure above that required to lift the gravity valve against atmospheric pressure; oil then flows out at a time when no lubrication is required, and that amount of oil is thereby wasted. 110

My invention applied in the force feed lubricator system of a locomotive is illustrated in the accompanying drawings wherein like characters indicate like parts throughout the several views. 115

Referring to the drawings,

Figure 1 is a view in side elevation show- 120

ing a locomotive partly in diagram and illustrating my invention incorporated in the force feed lubricating system thereof; and

5 Fig. 2 is an enlarged vertical section taken through the terminal check valve on the line $x^2 x^2$ on Fig. 1.

Of the parts of the locomotive, it is only desirable for the purposes of this case to 10 particularly note the boiler 1, the cab 2, the cylinders 3, and the steam chest 4. Of the parts of the lubricating system, it is only necessary to note the force feed lubricator proper (which includes the pumps), indicated as an entirety by the numeral 5, and one of the oil delivery pipes 6, which parts may be of the usual or any suitable construction, in which oil is adapted to be delivered to the coöperating steam chest 4 15 under the required high pressure. The delivery end of the said oil pipe 6 is connected to a threaded nipple 7 of a two-part easing 20 8—9 of the terminal check valve. The section 8 of the said terminal check valve is 25 provided with a depending threaded nipple 10 which is screwed into the top of the steam chest 4. Within the section 8 of this valve easing is a cylindrical valve seat 11, in which works a piston-like check valve 12, 30 which, as shown, is normally pressed downward by a coiled spring 13 made adjustable by a set screw 14, which is screwed into the upper end of the section 9 of the valve easing. An oil conduit 15 extends from the re- 35 ceiving end of the nipple 7 to the bottom of the cylinder-like valve seat 11, and another oil delivery conduit 16 extends from one side of the said valve seat 11, to the delivery end of the nipple 10. In the construction 40 illustrated, the valve 12 is provided at its intermediate portion with an annular oil groove or port 17 which is in constant communication with an axial oil conduit 18 that extends from the said port 17 down- 45 ward to the extreme lower end of the said valve.

It will, of course, be understood that the 50 spring 13 must be set under such tension that the said valve will be opened, by up- 55 ward movements, causing its port 17 to align with the receiving end of the conduit 16, only by a pressure which exceeds the normal maximum steam chest pressure, or pressure against which the pumps of the 60 lubricator must work to cause the delivery of oil into the said steam chest or oil receiving chamber.

When this is done, the various desired and very much improved actions above fully 65 described will, of course, take place.

Obviously, when oil which is forced into the conduit 15, equals or exceeds the assumed pressure of 250 pounds per square inch, under which the said terminal check valve 65 is set to open, the port 17 coming into con-

tact with the receiving end of the conduit 16 allows oil to flow into the steam chest. On the other hand, when the pressure in the oil pipe 6 falls below 250 pounds (assumed to be the operative pressure), the said terminal check valve will close and cut off communication between the conduits 15 and 16. Thus a pressure equal to the tension of the spring 13 on the area of a valve, is maintained in the oil pipe 6, whether or not oil is being discharged therefrom or fed therethrough.

In practice, the above described lubricator, with its check valve set to open only under pressure, exceeding that against which the oil is fed, has been found highly efficient for use in connection with locomotives, but it will be found useful when applied to internal combustion engines, and elsewhere, where oil must be fed against fluctuating pressures. It is also desirable for use even in connection with ordinary stationary engines. The statements made in this paragraph are especially true in respect to a check valve which discharges at 90 a higher oil pressure than the steam pressure and in which the steam pressure is entirely balanced, or nearly so, within the valve, as is the case of the piston check valve where the steam has access to the annular oil 95 groove on the piston when the piston is in the discharge position, so that the upward and downward steam pressure components acting on the valve equalize each other and the steam pressure, therefore, is eliminated 100 from effecting a movement of the valve. This is a distinguishing difference between our valve and a gravity needle check valve made to lift at a higher pressure than the steam, in which case the steam pressure 105 would not be eliminated from effecting the movement of the valve, but would act against the movement of it, and would add the steam pressure to the resistance of the valve itself.

When the locomotive is standing still and the oil pump is not working, oil is trapped in the oil conduit between the pump and the piston valve 12, under a predetermined pressure. The chamber in which the piston 115 valve 12 is mounted affords an intermediate oil chamber, and the lower end of said valve serves as that portion of the valve mechanism which is exposed to the pressure of the oil in the conduit. The lower end of 120 the valve, or the portion exposed to the pressure of the oil in the conduit, is cut off from the cylinder pressure by another portion of the valve mechanism, to wit, the side wall of the piston valve. The valve is, 125 therefore, not affected by the back fluid pressure from the cylinder.

In this specification and in the claim, the term "pressure" is used in a liberal sense to include partial vacuum or a pressure which 130

is below atmospheric pressure, and which is frequently designated as a "negative pressure."

What I claim is:

- 5 The combination with a locomotive, of a lubricating system therefor, comprising an oil pump driven from the running parts of said locomotive, oil delivery conduits leading from said pump, and terminal valve mechanisms each of which has one part for controlling the discharge of oil from its conduit to the corresponding cylinder and another part exposed to the pressure of the oil in the conduit, but cut-off by said first-
10 noted part, from materially effective back
- 15

pressure from the cylinder, and yielding means operative to close said valve mechanism in opposition to a predetermined oil pressure that at least equals the maximum variable fluid back pressure from the cylinders, but permitting said valve mechanism to open under an oil pressure that exceeds said maximum predetermined pressure.

20

In testimony whereof I affix my signature in presence of two witnesses.

ROBERT L. McINTOSH.
